LIGHTER

Darold B. Hickman, North Attleboro, Mass., assignor to Evans Case Company, North Attleboro, Mass., a corporation of Massachusetts

Application September 13, 1943, Serial No. 502,211

5 Claims. (Cl. 67—7.1)

The invention relates to lighters and especially so-called pocket-lighters of the class carried in the pocket or in a handbag or pocketbook or other portable receptacle. Such devices have means for starting a flame. Inasmuch as they are used in all sorts of places, frequently the air movements, drafts, or winds are such as to blow the flame undesirably or to extinguish it. Of course it is desirable that the flame be kept burning clearly long enough to ignite a cigarette, cigar, 10 pipe, or the like.

A purpose of the present invention is to provide such lighters with a shield or device for protecting the flame from drafts, winds, and the like. Means may be employed which may be 15 fastened in place or may be removable or separate from the lighter structure itself and the shield and the casing, of which the shield forms a part, may be made separately and applied to lighters. Thus, the casing or shield may be made of the same or different material from that of the lighter and may be decorated or ornamented in any suitable manner. The lighters may be made in quantity and casings carrying shields 20 may be made in quantity, and orders may be filled by selecting casings which will produce the desired external ornamental effect or appearance of the lighter.

In the accompanying drawing is shown one form the invention may take. Figure 1 is a front elevation of a lighter incorporating the present invention. Figure 2 is a side elevation of the same. Figure 3 is a side elevation similar to Figure 2, with portions broken away to show the construction and arrangement of parts. Figure 4 is a horizontal cross section on line 4—4 of Figure 3.

A typical lighter 10 is shown having a relatively flat top wall 11 from which projects a wick 12 which may be ignited into a flame 13 by means of any suitable well known mechanism indicated generally at 14. The lighter itself and its parts and general operation form no part of the present invention which may be applied to any lighter. For this reason lighter details are not shown and are not limits to the invention. A shield for the flame is provided by means of a front member 15 extending above the top wall 11 and the wick 12 near the flame 13 and connected to side members 16, 17. The members 15, 16 and 17 are preferably imperforate and form a satisfactory shield for protecting the flame 13 on the wick 12 from the influence of air movements in the neighborhood of the lighter. The front member 15 and side members 16 and 17

17 extend downwardly at 18 to enclose substantially the entire lighter 10. At the bottom of the lighter 10 is a projecting plate or rib 19 which, as shown, may be slightly larger in dimensions than the lighter itself and extends under the bottom end of the casing 18 so as to form a seat therefor. This limits movement of the casing when it is inserted on and about the lighter 10. When in place frictional engagement of the lighter and the casing may be relied on to hold it in place, and it may thus be readily removable or replaceable by a casing of different appearance or ornament. The casing, however, may be welded, riveted or otherwise held in place on the lighter.

The portion 20 of the casing 18 which extends downwardly below the front 15 of the shield is spaced somewhat away from the front of the lighter 10, thus forming a chimney-like channel 21 which is closed at its bottom by the base member 19 of the lighter 10. Although it is desirable to keep drafts and winds away from the flame 13, it is also desirable to supply to the flame 13 sufficient air to support combustion of the flame. 25 The member 19 may be reduced or omitted, allowing air to enter at the bottom of the channel 21, in which event it may be possible to rely on air entering at the bottom of the channel 21 to support combustion of the flame 13. Slots or openings 22 may be provided in the front 20 of the casing 18. These slots or openings may be of any suitable size and any suitable number. These slots are all below the top 11 of the lighter 10 so that when the lighter operates in a wind the flame is protected by the shield members 15, 16 and 17 from direct draft. The wind entering the slots 22 impinges against the front of the lighter 10 and passes upwardly through the chimney-like channel 21, quietly feeding sufficient air to the flame 13 to continuously and satisfactorily support combustion. The amount and force of the air reaching the flame may be controlled if desired by covering one or more of the slots 22 by the fingers or in any other suitable way.

As an aid in further protecting the flame from the incoming air, it may be desirable in some instances, especially when the wick is arranged near the front edge of the lighter, to provide a baffle 23 at or near the top of the lighter 10 which may cause air rising in the channel 21 to be deflected away from the flame 13 and cause it to impinge against the front 15 to reduce its momentum before it reaches the flame 13.

The casing 18 may be made to come substan-

tially in contact with the lighter at all points except at the channel or passage-way 21.

The invention is not limited to the specific form shown but may be embodied in other apparatus.

I claim as my invention:

1. In a lighter having a wick projecting from its top wall, an imperforate shield extending above the top wall on three sides of the wick, a downwardly extending portion of the shield comprising sides engaging the lighter, and a third member joining the extending sides but out of contact with the lighter.

2. In a lighter having a wick projecting from its top wall, an imperforate shield extending above the top wall on three sides of the wick, a downwardly extending portion of the shield comprising sides engaging the lighter, and a third member joining the extending sides but out of contact with the lighter and provided with perforations below the top of the lighter.

3. In a lighter having a projecting wick, a casing having sides engaging the lighter and a perforate end out of contact with the lighter, the sides and end having extending imperforate portions forming a shield for the wick.

4. A casing surrounding and engaging a lighter but out of contact with the lighter at one part of its cross section and provided with perforations at the out-of-contact portion, the casing having an imperforate portion extending beyond the body of the lighter forming a shield for the lighter flame.

5. In a lighter having a wick projecting from its top wall, an imperforate shield extending above the top wall on three sides of the wick, a downwardly extending portion of the shield comprising sides engaging the lighter, a third member joining the extending sides but out of contact with the lighter, and a baffle at about the top of the lighter extending toward the third member.

DAROLD B. HICKMAN.
